UNITED STATES PATENT OFFICE

ALFRED SCHNEIDER, OF BERKELEY, CALIFORNIA, ASSIGNOR TO LIBERTY BURNER CORPORATION, OF SAN FRANCISCO, CALIFORNIA, A CORPORATION OF DELAWARE

FLUID PUMP STRUCTURE

Application filed April 22, 1929. Serial No. 357,015.

This invention relates to fluid pumps and particularly to a pump designed for use with liquid fuel oil burners.

Among its objects, the invention provides 5 a self priming pump, one of the double valve type, wherein two separate bodies of fluid are in communication through valve controlled ports and are maintained flowing by the operation of a pump mechanism. A further 10 object is to provide a pump structure having a simple valve and seat structure in the check valve chamber thereof. Further objects are to provide a novel form of pump structure secured in position to the valve mechanism 15 in a particular manner which promotes simplicity and cheapness in structure, and to provide a fluid accumulating chamber connected with the fluid inlet of the valve structure.

20 With the above mentioned and other objects in view, the invention consists in the novel construction and combination of parts hereinafter described, illustrated in the accompanying drawings and pointed out in the 25 claim hereto appended; it being understood that various changes in the form, proportion, size and minor details of construction within the scope of the claim may be resorted to without departing from the spirit or sacrificing any of the advantages of the invention.

To more clearly comprehend the invention, reference is directed to the accompanying drawing, wherein:—

The figure is a view in vertical central 35 section of one embodiment of my invention.

In the drawing, 1 indicates a body preferably of elongated, cylindrical structure, and normally disposed in a vertical or upright position. The body is preferably of 40 metal and on its interior is recessed downwardly from its upper end at 2 for approximately one-half of its length, the recess being formed at its upper end through its side wall with a fluid discharge 3, and at its lower end 45 through its side wall with a fluid inlet 4, the latter opening into the center of the base or bottom of the chamber at 5. The bottom wall of the body is provided with one or more flow passages 6' extending vertically there- 50 through. Attached to the lower end of the

body 1, preferably in a permanent manner, is the upper end of a pump cylinder 6 of the 55 linearly expansible and contractable type, circumferentially bellowsed and commonly known as a sylphon, these structures being purchasable on the open market.

The recess 2 is divided transversely into upper and lower pressure chambers 7 and 8 by a cupped part 9 threadably positioned 60 within the recess through its upper open end and formed with passages 10 therethrough. The periphery of the cup in member 9 affords a valve seat 11 and a valve stem guide 12 is provided in its base. The upper end of recess 2 is closed by a removable plug 13 65 threaded into the body and formed on its underside with a valve stem guide.

Within the respective chambers 7 and 8 are mounted the spring seated check valves 14 and 15 of duplicate structure, the valve 14 70 seating on 11 and the valve 15 seating as at 16.

A tubular extension 17 is threaded into inlet 4 with its inlet 18 downwardly disposed. The extension 17 passes through a 75 member 19 and holds the same in position to the body 1. The member 19 is disposed parallel with body 1 and extends above and below the inlet 4, its interior affording a fluid accumulating chamber 20 having a 80 screened fluid inlet 21 at its lower end.

On its expansion or suction stroke the cylinder 6 draws fluid into the chamber 20 through 18 and 4 and lifts valve 15. The fluid passes into chamber 8 and into the cylinder 6, and all compartments below valve 14 85 are substantially filled. On the compression stroke, the fluid in cylinder 6 and chamber 8 is displaced and is forced into chamber 7 and out through discharge 3, after lifting valve 14.

It will be observed that the arrangement of the valves and chambers provides a self priming structure of positive and efficient operation, which is simple in construction 95 and which will handle fluids economically.

I claim:—

The combination with a reciprocating pump, of a pump structure comprising a recessed body having a passage between the 100

closed end of the recess and the pump, said body being provided with intake and discharge passages opening upon the closed and open end portions of the recess respectively,
5 a removable ported wall positioned within the recess between the intake and discharge passages, a valve slidably mounted in the removable wall and adapted to seat over the intake passage, a valve slidably mounted in
10 the open end of the recess, and a closure for the open end.

In testimony whereof I have signed my name to this specification.

ALFRED SCHNEIDER.
